UNITED STATES PATENT OFFICE

135,267

DESIGN FOR A FIGURE TOY OR THE LIKE

Thomas Lamb, New York, N. Y.

Application February 21, 1942, Serial No. 105,948

Term of patent 7 years

To all whom it may concern:

Be it known that I, Thomas Lamb, a citizen of the United States of America and a resident of New York, in the county of New York and State of New York, have invented a new, original, and ornamental Design for a Figure Toy or the like, of which the following is a specification, reference being had to the accompanying drawings, forming a part thereof.

Figures 1, 2 and 3 are side, rear and front elevational views, respectively, of the figure toy or the like showing my new design; and

Figures 4 and 5 are front perspective views of the same.

I claim:

The ornamental design for a figure toy or the like, as shown.

THOMAS LAMB.
